UNITED STATES PATENT OFFICE.

WILFRED DUPRÉ, OF WORCESTER, MASSACHUSETTS.

BROOM.

Application filed April 23, 1924. Serial No. 708,553.

This invention relates to a broom having a detachable filler.

The principal objects of the invention are to provide means for holding a filler in such a way that it can be reversed and when reversed the dirty and worn ends of the filler will not be visible; to provide a holding means in such form that the filler can be guided into it easily and held temporarily while being properly mounted therein; to provide the holder with a cover adapted to be secured firmly in position so as to hold the filler just as firmly as is the case with an ordinary broom; to avoid the expense of winding the 10 filler so as to secure it to the handle; to provide a filler constructed in such a way that all the fibers are held firmly in position and yet it is flexible at the center so that one end can be contracted and that will expand or 15 spread the other end so that it will assume substantially the shape of an ordinary broom, and to provide improvements in the details of the means for holding and supporting the 20 filler and connecting it with the handle.

Other objects and advantages of the invention will appear hereinafter.

Reference is to be had to the accompanying drawings, in which—

Fig. 1 is a front elevation of a broom constructed in accordance with this invention and shown in position for sweeping;

Fig. 2 is an edge view of the same;

Fig. 3 is a view similar to Fig. 1 of the filler removed from the handle and holder;

Fig. 4 is a sectional view on the line 4—4 of Fig. 3 on enlarged scale;

Fig. 5 is a front view of the holder open with the filler removed;

Fig. 6 is a longitudinal sectional view of the same partly open and taken on the line 40 6—6 of Fig. 5; and

Fig. 7 is an end view.

This invention relates to that type of broom in which a double ended reversible filler is used, formed of broom corn or the like so that the life of the broom will be doubled. In the present case this filler is formed in sections. The fibers 10 of broom corn are laid parallel with each other and of a length substantially equal to the length of two brooms below the point at which the fibers are usually sewed together. They are cut off square at both ends and both ends are made alike. The fibers are collected in sections 11 of convenient size, preferably about as thick as they are wide. The fibers of each section are inde-

pendently and permanently connected together at the center by the use of suitable plastic cementing material as tar, glue or any composition that can be used for that purpose. 60 The composition is impregnated throughout the fibers of each section so that each fiber will come into contact with it and be held in place by it, thus preventing the fibers pulling out from either end. 65

A series of sections of fibers 11 are placed side by side to form any desired width of broom and they can be sewed through in the usual way, if desired, as indicated by the threads 12. Either before or after this sewing they are bound all around with one or more layers 13 of tape or other suitable material and that is secured in place by the sewing above mentioned or in any other convenient way. This construction forms a double ended broom filler made up in sections as stated so that when the fibers at one end are brought close together, that is, contracted, the sections of fibers can swing or pivot about their centers on account of the flexibility of 75 the connections between the sections and the other end of the filler will be spread or expanded, as shown in Fig. 1. This permits of the mounting of the filler in the holder which I have provided and the location of the fibers 80 in their natural relationship so that it will look like an ordinary broom and can be used in the same way. 85

For the purpose of holding this filler I have provided a holder comprising a casing 90 20 of sheet metal, preferably, having a back or floor of tapering shape. That is, its side edges converge toward each other at the upper end. These side edges 21 which are integral with the back extend at right angles to the plane of the back and then are bent over to form flanges 22 spaced materially from the back so as to receive the filler in under these flanges and prevent those fibers at the edges 95 from working out loose. 100

I have shown the flanges as provided with perforations 23 and a curved wire 24 held therein and loosely pivoted thereto for the purpose of temporarily holding the free ends of the filler when it is forced up into the casing. At the open end of the casing I have shown the sheet metal at the back doubled over on itself and provided with two corrugations 25. These corrugations are shown as provided with perforations, the edges of 110 which are stuck up outwardly to form prongs 26 adapted to project into the body of the 105

filler and hold the latter firmly in position. The back end flanges are also provided with perforations 27 at opposite sides through which fastening bolts 28 are adapted to pass.

5 The upper end of the casing has a curved extension 29 which passes around a cross piece 30 which may be of cylindrical or any other desired shape. This cross piece preferably is of wood and is provided with enlargements 10 31 at its ends projecting beyond the sheet metal extension 29. This cross piece is for the purpose of holding the handle 32 which is of any ordinary kind. The handle preferably extends into a perforation in the cross piece 15 30 and is held therein in any of the ordinary ways.

Pivottally secured to the sheet metal extension 29 by means of a hinge 33 or the like, is a cover 34. This cover preferably also is 20 made of sheet metal in a single piece and has converging side flanges 35 adapted to overlap the sides 21 and having a shape to fit them. This piece is also doubled on itself to form inward corrugations 36 having teeth or 25 prongs 37 like those of the casing and located opposite them. Two series are shown. It will be noted that in both the casing and cover the end walls 38 are formed straight across at their adjacent sides but convex on their 30 rear or outer sides. This is to provide additional strength. The casing and cover, in other words, are convex at the ends for the purpose of strengthening them. The cover is also provided with perforations for receiving 35 the fastening screws or bolts 28 and thumb nuts 39 are employed for fastening the two parts together.

In the use of the device, one end of the filler is grasped in the hands and contracted so 40 that it can be forced into the casing 20 when it is open, as shown in Fig. 5. The edges of the filler will pass in under the flanges 22 and the ends of the fibers of broom corn or the like will be held under the wire 24. If 45 it is shoved in as far as it will go it can be released and will not get out of position while the cover 34 is swung down into closed posi-

tion, as shown in Figs. 1, 2 and 7. The screws or bolts 28 pass into the openings in the cover and the thumb nuts 39 are then applied and 50 screwed down to hold the teeth 26 and 37 securely against the broom corn of the filler at a point just above the tape 13. This effectively holds the parts in position and permits 55 of the use of the broom in ordinary ways. 55

This broom is light and durable. Without refilling, it has twice the durability of the ordinary broom and when the filler has been used up on both ends it can be discarded and a new filler applied. The filler itself is manufactured much less expensively than is the ordinary broom because it does not have to be permanently attached to the handle and all the winding of wire around through the fibers is avoided. Yet the filler is immovably and 60 securely held in position in the holder and it does not have any chance of becoming loose. Furthermore, the bristles are firmly held in position and yet the filler is made flexible laterally so that it can assume the position 70 above described and shown clearly in Fig. 1.

Although I have illustrated and described only a single form of the invention I am aware of the fact that modifications can be made therein by any person skilled in the art 75 without departing from the scope of the invention as expressed in the claim. Therefore I do not wish to be limited to all the details of construction herein shown and described but what I do claim is:

In a broom, the combination with a filler, of a metal casing having a back and sides for receiving, and a metal cover for covering the forward end of the filler, said casing and cover having teeth along one edge for engaging the opposite sides of the filler and holding it, the metal at the said edges being doubled over the inner surfaces of the casing and cover, the metal along said edges being convex outside and straight on the inside. 85 90

In testimony whereof I have hereunto affixed my signature.

WILFRED DUPRÉ.
